UNITED STATES PATENT OFFICE.

JACOB FLOURNOY BARKER, OF CARTHAGE, MISSOURI.

DESIGN FOR A DRILL-HEAD.

SPECIFICATION forming part of Design No. 32,219, dated February 13, 1900.

Application filed January 15, 1900. Serial No. 1,572. Term of patent 14 years.

To all whom it may concern:

Be it known that I, JACOB FLOURNOY BARKER, of Carthage, Jasper county, State of Missouri, have invented a new and original 5 Design for a Drill-Head, of which the following is a full, clear, and exact description, reference being had to the accompanying drawings, forming a part hereof.

Figure 1 is a side elevation of my newly-invented design. Fig. 2 is a top plan view of same.

The leading or material feature of my design consists of a body 1, having in plan view substantially the shape of a Greek cross and 15 comprising a series of radial webs 2, connected at their inner ends and separated at their outer ends and provided thereat with

enlargements 3, which are approximately T-shaped in plan view. The upper ends of the said webs are formed at an angle, and the 20 whole is surmounted by a cap or shank 4, having a conical outline. The lower or cutting edge of the said webs is flared outwardly at 5.

I claim—

The design for a drill-head, substantially as herein shown and described.

In testimony whereof I affix my signature in presence of two witnesses.

JACOB FLOURNOY BARKER.

Witnesses:

CARRIE BARRATT,
WOODFORD SHANNON.
